UNITED STATES PATENT OFFICE.

THOMAS WILLIAM CRANE, OF IMPERIAL, CALIFORNIA.

FEED TIP FOR LUBRICATORS.

Original application filed August 30, 1922, Serial No. 585,296. Divided and this application filed December 15, 1923. Serial No. 680,910.

To all whom it may concern:

Be it known that I, THOMAS WILLIAM CRANE, a citizen of the United States, residing at Imperial, in the county of Imperial, State of California, have invented certain new and useful Improvements in Feed Tips for Lubricators, of which the following is a specification.

This invention relates to improvements in feed tips for lubricators, and it consists in the combinations, constructions and arrangements herein described and claimed.

More specifically, the present invention is a divisional part of that disclosed in my prior application for Letters Patent of the United States, Serial No. 585,296, filed August 30, 1922.

An object of the present invention is to provide a novel feed tip of simple construction which is adapted for application to a lubricator attached to a rotating or oscillating part and which has facilities for controlling the flow of a lubricating fluid therethrough to the bearing of the part to which the lubricator is applied, whereby a determined quantity of the lubricating fluid will be fed to the bearing during each operating movement of the part to which the lubricator is attached and the feeding of the lubricating fluid to the bearing will be discontinued co-incidently with the cessation of operating movement of the part carrying the lubricator.

Other objects and advantages will be apparent from the following description, considered in conjunction with the accompanying drawings, in which:

Figure 1 is a perspective view showing a lubricator equipped with the present invention and applied to a supporting part.

Figure 2 is a relatively enlarged central vertical section through the structure exhibited in Figure 1, and

Figure 3 is a section along the line 3—3 of Fig. 2.

Referring now to the drawings, a lubricant container or cup is indicated generally at 1. This lubricant container preferably comprises an outer shell 2 having a fill opening 3 at one end thereof and being provided

at its other end with a central boss 4 having an axial bore 5 which constitutes an outlet or discharge opening for the lubricant container. The lubricant container also may include an inner casing 6 which is open at the end thereof proximate to the outlet 5 and is provided at its opposite end with an end wall 7 connected by integral web portions 8 so that the inner casing 6 will be held in spaced concentric relation to the outer shell 2, and a fill opening 9 through the end wall 7 will be in alignment with the fill opening 3. The fill openings 3 and 9 have threaded walls and the fill opening 9 is of less area than the fill opening 3 so that a screw plug 10 may be inserted through the fill opening 3 into engagement with the fill opening 9 and a larger screw plug 11 then secured in the fill opening 3. The inner casing 6 terminates short of the confronting end wall of the outer shell.

The boss 4 is provided with a counterbore 12 at the outer end of the bore 5, the walls of the counterbore being screw-threaded. The boss 4 also is provided with a lateral opening 13 which extends transversely thereinto from one side wall thereof and intersects the bore 5. The lateral opening 13 does not extend through the opposite wall of the boss. The wall of the opening 13 is screw threaded for engagement with a screw plug 14 which serves as a valve and may be manipulated to control the passage of a lubricating fluid from the container 1 through the bore 5.

The boss 4 has the outer end portion thereof reduced in diameter at 15 and provided with external screw threads for engaging a tubular nozzle 16, packing such as indicated at 17 preferably being compressed between the shoulder 18 at the inner end of the reduced portion 15 and the adjacent end of the nozzle 16. The nozzle 16 is provided with a screw-threaded end portion 19 which is adapted for connection with the internally screw-threaded inlet 20 of a bearing to which the lubricant is to be fed. The reduced end portion 19 of the nozzle has a bore 21 of restricted area extending therethrough and constituting a dis-

charge opening through which lubricant may pass from the chamber or space 22 within the nozzle through the inlet 20.

The present invention is concerned primarily with the provision of a novel feed tip for controlling the flow of lubricant from the bore 5 into the chamber 22 of the nozzle, it, of course, being understood that lubricant is permitted to pass along the bore 5 only when the valve 14 is in open position. The feed tip embodying the invention comprises a tubular body 23 having a slightly enlarged externally screw-threaded end portion 24 adapted for connection with the counterbore 12. The tubular body 23 is open at its opposite ends and the free end portion thereof is provided with a spiral rib 25 which preferably is integral therewith and which is secured in any suitable known manner, as by welding, to the inner wall of a cup-shaped shell or cap 26 which encompasses the free end portion of the body 23 and is disposed with the bottom wall thereof in spaced confronting relation to the open free end of the body 23, thus providing within the cap 26 a compartment or space 27 at the bottom thereof and at the free end of the body 23, which space communicates with the chamber within the nozzle 16 through a spiral passage 28 which is defined by the spiral rib 25 in conjunction with the inner wall of the cap 26 and the outer wall of the portion of the tubular body 23 which is disposed within the cap.

From the foregoing description of the various parts of the device, the operation thereof may be readily understood. The container 1 may be filled with a suitable lubricant which will flow readily. This will be accomplished when the container is in upright position since as hereinbefore stated, the device is intended primarily for use with a lubricator carried by a rotating or oscillating part. It will also be understood that the valve 14 will be in closed position when the container is filled. The valve 14 then is opened and as the part to which the nozzle 16 is attached rotates, the lubricant which has passed through the bore 5 and the tubular body 23 into the space 27 of the cap 26 will pass through the spiral passage into the compartment 22 of the nozzle and thence to the bearing of the rotating or oscillating part. The spiral rib 25 is of such length and so arranged in respect to the tubular body 23 that the opposite ends of the spiral passage will lie in different horizontal planes when the body 23 is in horizontal position, whereby lubricant will pass through the spiral passage only during part of the rotational or oscillatory movement of the part to which the lubricator is attached. In consequence, the feeding of lubricating fluid to the bearing will be regularly intermittent during rotation of the part to which the

device is applied. It is desirable that the device be applied to a part rotating at a moderate speed or slackened in rotational speed at intervals in order that the feeding of the lubricating fluid to the bearing may not be detrimentally affected by centrifugal force as might be the case were the part to rotate continuously at high speed.

Obviously, the invention is susceptible of embodiment in forms other than that illustrated in the accompanying drawings and I, therefore, consider as my own all modifications and adaptations thereof which fairly fall within the scope of the appended claims.

I claim:

1. In a device of the character described, the combination with a tubular outlet communicating at one end with a source of lubricating fluid supply, of a feed tip comprising a tubular body secured at one end to the tubular outlet in open communication with the latter, a cap encompassing the free end portion of said tubular feed tip body, and means connecting said tubular feed tip body and said cap for holding the latter in spaced relation to the tubular feed tip body and for providing a spiral passage between the confronting walls of the tubular feed tip body and cap.

2. In a device of the character described, the combination with a tubular outlet communicating at one end with a source of lubricating fluid supply, of a feed tip comprising a tubular body secured adjacent to one end within the bore of the tubular outlet, said tubular feed tip body having a spiral rib on the outer wall thereof, a cap encompassing the free end portion of said feed tip body and secured to the peripheral walls of said spiral rib, whereby said cap will be spaced from said feed tip body and a spiral passage is provided between the confronting walls of the feed tip body and the cap thereon.

3. In a device of the character described, the combination with a tubular outlet communicating at one end with a source of lubricating fluid supply, of a feed tip comprising a tubular body secured adjacent to one end within the bore of the tubular outlet, said tubular body having a spiral rib on the outer wall thereof, a cap encompassing the free end portion of said feed tip body and secured to the peripheral walls of said spiral rib, whereby said cap will be spaced from said feed tip body and a spiral passage is provided between the confronting walls of the feed tip body and the cap thereon, said spiral passage terminating at its opposite ends in different horizontal planes when the feed tip body is in horizontal position.

4. In a device of the character described, a tubular outlet having a bore communicat-

ing at one end with a source of lubricating fluid supply, a feed tip comprising a tubular body secured adjacent to one of its ends within the bore of said tubular outlet, said feed tip body having an integral spiral rib on the protruding portion thereof, and a cap encompassing the protruding portion of said feed tip body and being permanently attached to the spiral rib, said cap having

the end wall thereof disposed in spaced relation to the open end of said feed tip body, thus providing a space within the cap at the free end of the feed tip body and in communication through the spiral passage extending between the convolutions of the 15 rib with the space exterior of the cap.

THOMAS WILLIAM CRANE.
